BREAST BOX FOR PAPER MACHINES

Frank H. Williams, Dalton, Mass., assignor to
 Crane & Co., Inc., Dalton, Mass., a corporation
 of Massachusetts

Application June 12, 1940, Serial No. 340,086

14 Claims. (Cl. 92—44)

This invention relates to improvements in paper-making apparatus and is directed more particularly to improvements in a breast box construction adapted for use with paper making machines of the Fourdrinier type.

The principal objects of the invention are directed to the provision of a breast box which is characterized by relatively movable co-operating forward and rear sections arranged and adapted for association with the breast roll and shake mechanism and screen of the paper making machine in such a manner that paper making material is delivered from the screen to the novel breast box and then onto the wire.

According to certain novel features of the invention the construction and arrangement is such that there is a greatly improved leveling, and intermixing or intermingling of the paper making fibers which brings about an improved paper formation and strength of web.

The improved mixing of fibers and their uniform distribution results in paper having desirable characteristics as to formation, strength, and texture not only as is desired in some particular grades but more generally in connection with all grades where are concerned such important considerations as closeness of formation, strength, etc.

According to other novel features of the invention not only is it possible to provide the desired strength and closeness of formation with respect to various grades of paper but the speed of the paper machine may be increased without impairing the improved characteristics of the paper resulting from the use of the apparatus.

According to further features of the invention the construction is such that there is a relatively small loss of stock on shut downs and the rather shallow construction of the novel breast box facilitates ease of control when starting the paper machine on a run.

According to still further features of the invention the novel breast box is constructed of metal to facilitate ease in cleaning and providing rigidity and strength while at the same time the stock is delivered to the wire substantially free from strings and lumps.

The novel breast box of the invention embodies numerous other features to provide many other new and varied advantages as will appear from the following description of the present preferred form of the invention.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more

fully described and referred to in connection with the accompanying drawings wherein:

Fig. 1 is a side elevational view of a breast box embodying the novel features of my invention and shown in association with the breast-roll and screen of a paper-making machine;

Fig. 2 is a longitudinal elevational sectional view of the breast box shown in Fig. 1; and

Fig. 3 is a plan view of the breast box shown in Figs. 1 and 2.

Referring now to the drawings more in detail, the invention will be fully explained.

It will be understood that the novel features of the invention are adapted for use in connection with various Fourdrinier paper making machines and that the embodiment of the invention to be described is for purposes of disclosure only since modifications and changes may be made without departing from the spirit and scope of the invention.

In a broad way the breast box of the invention includes a rear section indicated by 2 and a forward section indicated by 4. The rear section is adapted to be associated with the screen apparatus of a paper machine while the forward section which is movable relative to the rear section may be associated with the wet end of the machine at the breast roll.

With reference to the drawings, Fig. 1, as shown, the reference 6 represents the forward wall of a screen to which opposite side walls 8 of the rear section 2 may be secured by any suitable means such as bolts 10 to facilitate up and down movements of said side walls and the securing thereof in adjusted positions. The side walls 6, as shown in Fig. 3, are arranged in diverging relation and spaced supports 11 which are disposed therebelow have blocks 12 thereon which threadedly receive adjusting screws 14. The upper ends of the adjusting screws 14 abut members 16 of a transverse member 18 which supports the side walls at their forward ends. The member 18 may be clamped to the supports 11 in adjusted positions by means of bolts such as 20 or the like. The side walls 8 may be adjusted up and down to any desired position of adjustment by means of the bolts 14 and are tied together by means later to be described.

Side walls 24 of the forward section of the breast box are disposed outside of the side walls 8 and they are connected together and held in spaced relation by means to be later described.

A breast roll is represented by 26 which is journaled in the usual manner for rotation in brackets 28 pivoted on horizontal axes in members 30 on either side of the machine. The brackets and breast roll are vibrated back and forth transversely of the machine in the usual manner by any suitable vibrating mechanism not shown. Brackets such as 32 there being one on

each side of the machine, are for supporting the shaft or shafts of the usual deckle strap pulleys, not shown.

A plate construction indicated generally by 34 extends between the side walls 24 of the forward section and consists of a frame formed by transverse members 36 and 38 and end members such as 40. There may be other longitudinal members between members 36 and 38 although not shown. These members 36, 38 and 40 support a plate 42 and said members are secured together in any suitable manner and to the plate to provide a strong rigid plate structure.

Other members such as 44 and 46 extend between the walls 24 and adjusting bolts 48 or screws associated therewith abut lugs such as 50 of the end members 40. By means of the bolts 48 the plate structure 34 may be adjusted up and down for adjusting and leveling purposes. Screws or bolts 52 threadedly engaging the side walls 24 are disposed in slots of the members 40, as shown, to provide a means for clamping the plate structure in a desired position of adjustment. Other means than shown may be used for adjusting and securing the plate 42 in place.

A support 56 extends between and is secured to the side walls 8 adjacent the forward portions thereof. This support in a form of the invention shown is preferably tubular in form to provide rounding surfaces, as shown, and connected to the walls 8 serves to hold them in spaced relation.

A bottom plate or wall 58 extends forwardly from the screen and generally in a downwardly direction and is secured at opposite sides to the side walls 8.

Said plate 58 curves forwardly and downwardly and while continuing forwardly more or less it extends upwardly and rearwardly through a generally semi-circular portion below and adjacent the rear side of the support 56 and finally continues around the member 56 and terminates at 62 forwardly thereof.

The plate 58 may be of any suitable material but will be preferably of sheet metal such as relatively thin copper or the like. To reinforce the forward end portion as may be necessary and desired, a transverse reinforcing member of any desired form may be secured thereto. Such a member is indicated generally by 64, but may take any form desired.

A pipe 68 extends between and is carried by the walls 24 of the forward section. Said pipe is arranged in such a manner that it is movable with the forward section and relative to the walls 8 to permit vibration of the forward section of the breast box when the forward section is vibrated.

Members 70 of the breast roll brackets 28 carry plates 72 to which are clamped as by bolts 74 a transverse member 76 associated with the walls 24. Adjusting screws 78 in threaded engagement with projections 80 abut members 82 so that as the adjusting screws are adjusted the forward end portion of the breast box forward section may be raised and lowered and clamped in the desired position of adjustment in which the forward section may be vibrated with the breast roll.

A support 94 extends between and is secured to the walls 24 and this may be similar to the support 56 already described. A plate or bottom wall 96 extending at its rear portion at least partly around the pipe 68 extends downwardly and forwardly to a curving or more or less semi-

circular section 98 and then upwardly and around the support 94 with the forward end 100 thereof extending somewhat beyond the said plate 42.

The pipe 68 and plate or wall 96 thereover are provided with apertures or discharge ports 69 for directing water upwardly and forwardly so that a spray thereof takes a generally forward and outward direction from between the upper rear portion of plate 96 and the forward portion 62 of plate 58. The said pipe 68 may, of course, be connected to any suitable source of supply.

On the plate 42 there is what may be called an apron member 102 which may be of any suitable material although a sheet of rubber or of rubber composition has been found to be satisfactory. The said apron member 102 extends beneath the forward portion 100 of the plate 96 and at its forward end it may extend beyond the plate 42 to some extent so as to overlie the Fourdrinier wire and the breast roll for delivery of paper making material thereonto. The side walls 24 of the forward section have outwardly extending portions 25 and the side marginal portions of the member 102 are carried outwardly and upwardly against said extension 25 while plates 106 clamp the marginal portions of the member 102 in place. It will be understood that the opposite marginal portions of member 102 may be secured to the walls 24, in any manner desired in order to close in the sides of the breast box. The particular construction described is not necessarily the only way in which this may be accomplished. The apron extends but a short distance beyond plate 42 onto the wire and does not necessarily require padding. The apron is readily changed due to the way it is carried by the flow box and is not secured as by nailing to a wooden strip as is sometimes the case. The plate 42 is readily adjustable for leveling and other purposes due to the novel construction.

A drain pipe may be provided for each of the breast box sections and are not shown as they form no part of the present invention.

From the foregoing it will be observed that the forward section of the breast box may be carried by the breast roll structure and is movable relative to the rear section so that as the breast roll and wire are vibrated back and forth the forward section of the breast box is vibrated therewith, the said forward section functioning as an additional making portion of the Fourdrinier machine so as to deliver the stock in the manner desired onto the wire.

The stock flows from the screen downwardly on the wall 58 and then upwardly and rearwardly and over and forwardly onto the wall 96 where in like manner it flows downwardly and upwardly and slightly rearwardly and finally up and over onto the apron. The general direction of the flow of the stock is indicated by the arrows. The forward section may be vibrated or have shake imparted thereto while the stock is flowing from the screen onto the wire.

The bottom walls 58 and 96 are constructed and arranged in combination with their associated parts in such a way that the stock is directed in a downward direction and is turned upwardly and then forwardly. The action is such that the stock is leveled and intermingled to bring about the desired uniform distribution and interfitting of fibers without such violent agitation as impairs the characteristics important in the finished paper. The spray pipe functions to enhance the desired movement or flow of the stock as it passes through the breast box

from one section to the other and further functions to prevent stock from running backwardly between the plates which would tend to cause lumps and strings.

It will be observed that the various elements of the novel breast box are independently adjustable in order to provide for the desired relative positioning of the parts to accommodate the apparatus to various conditions and produce various results, it being desired to level the stock and deliver it to the wire with the fibers properly intermingled and uniformly distributed so as to insure the desired formation, strength, and other important characteristics.

While I have described the invention in great detail and with respect to the present preferred form thereof, it is not desired to be limited thereto since changes and modifications may be made therein without departing from the spirit and scope of the invention. The invention may be embodied in other specific forms without departing from the essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What it is desired to claim and secure by Letters Patent of the United States is:

1. A breast box for a paper-making machine comprising in combination, separate forward and rear sections each having side walls, each section having a lower wall between said side walls that extends forwardly and downwardly and then curves upwardly and rearwardly and finally upwardly and forwardly with the forward end of the lower wall of the rear section extending over the rear end of the other lower wall.

2. A breast box for a paper-making machine comprising in combination, separate forward and rear sections each having side and lower walls, the lower wall of the forward section between the side walls thereof extending downwardly and forwardly and curving upwardly and rearwardly and then upwardly and forwardly, the lower wall of the rear section between the side walls thereof extending downwardly and forwardly and upwardly and rearwardly and then upwardly and forwardly over the rear end of said first named lower wall, the forward section being supported relative to the rear section for sideways vibrating movements.

3. A breast box for a paper-making machine comprising in combination, separate forward and rear sections adapted for relative sidewise shaking movements, each having side and bottom walls with the side walls of the rear section diverging outwardly and forwardly, the bottom walls of each section extending forwardly and downwardly and then curving upwardly and rearwardly and then upwardly and forwardly with the forward end of the bottom wall of the rear sections extending over and spaced from the rear end of the other bottom wall to provide a space, and a perforated pipe associated with the rear end of the bottom wall of the front section for directing liquid generally forwardly from said space.

4. A breast box for a paper-making machine comprising in combination, separate forward and rear sections adapted for relative sidewise shaking movements each having side and bottom

walls with the side walls of the rear section diverging outwardly and forwardly, the bottom walls of each section extending forwardly and downwardly and then curving upwardly and rearwardly and then upwardly and forwardly with the forward end of the bottom wall of the rear sections extending over and spaced from the rear end of the other bottom wall to provide a space, a perforated pipe associated with the rear end of the bottom wall of the front section for directing liquid generally forwardly from said space, and a substantially horizontal plate between the side walls of the forward section having its rear end disposed beneath the forward end of the bottom wall of the rear section.

5. A breast box for a paper-making machine comprising in combination, separate forward and rear sections adapted for relative sidewise shaking movements each having side and bottom walls with the side walls of the rear section diverging outwardly and forwardly, the bottom walls of each section extending forwardly and downwardly and then curving upwardly and rearwardly and then upwardly and forwardly with the forward end of the bottom wall of the rear sections extending over and spaced from the rear end of the other bottom wall to provide a space, a perforated pipe associated with the rear end of the bottom wall of the front section for directing liquid generally forwardly from said space, a substantially horizontal plate between the side walls of the forward section having its rear end disposed beneath the forward end of the bottom wall of the rear section, and means to adjust and hold said plate in various horizontal positions.

6. A breast box for a paper-making machine comprising in combination, separate forward and rear sections adapted for relative sidewise shaking movements each having side and bottom walls with the side walls of the rear section diverging outwardly and forwardly, the bottom walls of each section extending forwardly and downwardly and then curving upwardly and rearwardly and then upwardly and forwardly with the forward end of the bottom wall of the rear sections extending over and spaced from the rear end of the other bottom wall to provide a space, a perforated pipe associated with the rear end of the bottom wall of the front section for directing liquid generally forwardly from said space, a substantially horizontal plate between the side walls of the forward section having its rear end disposed beneath the forward end of the bottom wall of the rear section, means to adjust and hold said plate in various horizontal positions, and a member on said plate extending forwardly thereof and extending upwardly at the opposite sides thereof and secured to said side walls.

7. The combination with the movable breast roll supports at the sides of a paper-making machine and the forward wall of a screen spaced rearwardly therefrom and a breast box therebetween comprising, a rear section having diverging side walls adjustably secured at their rear ends to said screen, a forward section having side walls adjustably fixed at their forward ends to said supports, and supporting means at the rear end of the forward section to facilitate vibration of said section relative to the rear section with said breast roll supports, bottom walls for said sections each extending forwardly and downwardly and curving upwardly and rearwardly and then upwardly and forwardly with the for-

ward end of the wall of the rear section spaced above and overlying the rear end of the wall of the forward section, and a substantially horizontal plate between the side walls of the forward section extending forwardly of the bottom wall of said section with its forward end disposed so as to be adjacent a breast roll in said supports.

8. The combination with the movable breast roll supports at the sides of a paper-making machine and the forward wall of a screen spaced rearwardly therefrom and a breast box therebetween comprising, a rear section having diverging side walls adjustably secured at their rear ends to said screen, a forward section having side walls adjustably fixed at their forward ends to said supports, supporting means at the rear end of the forward section to facilitate vibration of said section relative to the rear section with said breast roll support, bottom walls for said sections each extending forwardly and downwardly and curving upwardly and rearwardly and then upwardly and forwardly with the forward end of the wall of the rear section spaced above and overlying the rear end of the wall of the forward section, a substantially horizontal plate between the side walls of the forward section extending forwardly of the bottom wall of said section with its forward end disposed so as to be adjacent a breast roll in said supports, and a member overlying said plate with its forward edge disposed to lie adjacent said breast roll and its side marginal edges associated with said side walls, and a pipe extending between the side walls of the forward section associated with the rear portion of the bottom wall thereof provided with outlets for directing fluid from between adjacent portions of adjacent bottom walls.

9. A breast box construction comprising in combination, front and rear relatively movable sections each having spaced side and bottom walls with the side walls of the rear section diverging outwardly from their rear ends, supports extending between the walls of said sections, that support for the rear section disposed adjacent the forward ends of the side walls thereof and that for forward section disposed intermediate the ends thereof, a perforated spray pipe extending between the rear portions of the side walls of the forward compartment forwardly of the support of the rear section, the upper and rear sides of said supports being in the form of cylinders, the bottom wall of the rear section extending forwardly and downwardly and then curving upwardly, rearwardly, and then upwardly and forwardly of and beyond the support of said section, the bottom wall of the forward section extending forwardly and downwardly from said spray pipe and curving upwardly and rearwardly and then upwardly and forwardly around the support of said section.

10. A breast box construction comprising in combination, front and rear relatively movable sections each having spaced side and bottom walls with the side walls of the rear section diverging outwardly from their rear ends, supports extending between the walls of said sections, that support for the rear section disposed adjacent the forward ends of the side walls thereof and that for forward section disposed intermediate the ends thereof, a perforated spray pipe extending between the rear portions of the

side walls of the forward compartment forwardly of the support of the rear section, the upper and rear sides of said supports being in the form of cylinders, the bottom wall of the rear section extending forwardly and downwardly and then curving upwardly, rearwardly, and then upwardly and forwardly of and beyond the support of said section, the bottom wall of the forward section extending forwardly and downwardly from

5 10 15

said spray pipe and curving upwardly and rearwardly and then upwardly and forwardly around the support of said section, and a plate between the side walls of the forward section forming a continuation of the forward end of the bottom wall thereof.

11. A breast box construction comprising in combination, spaced side walls, a bottom wall extending forwardly and downwardly and then upwardly, rearwardly and forwardly, an apron plate between said walls having its rear end beneath the forward end of said bottom wall, adjustable supporting means for adjusting and leveling said plate, and an apron on said plate having its forward end projecting therebeyond for overlying a Fourdrinier wire on a breast roll.

12. A breast box for a paper-making machine comprising in combination, separate forward and rear sections adapted for relative sidewise shaking movements each having side and bottom walls with the side walls of the rear section diverging outwardly and forwardly, the bottom walls of each section extending forwardly and downwardly and then curving upwardly and rearwardly and then upwardly and forwardly with the forward end of the bottom wall of the rear sections extending over and spaced from the rear end of the other bottom wall to provide a space, and a perforated pipe disposed adjacent the rear end of the bottom wall of the front section for directing liquid generally forwardly from said space.

13. A breast box for a paper-making machine comprising in combination, separate forward and rear sections each having side walls, each section having a lower wall between said side walls that extends forwardly and downwardly and then curves upwardly and rearwardly and finally upwardly and forwardly with the forward end of the lower wall of the rear section extending over the rear end of the other lower wall supporting means for the rear section and adjustable connections between said section and support.

14. A breast box for a paper-making machine comprising in combination, separate forward and rear sections each having side walls, each section having a lower wall between said side walls that extends forwardly and downwardly and then curves upwardly and rearwardly and finally upwardly and forwardly with the forward end of the lower wall of the rear section extending over the rear end of the lower wall, supporting means for the forward end of the forward section, and supporting means at the rear end of said section to permit sideways vibrating movements of said section relative to the rear section including, a transverse member below said forward section and rolls thereon journaled on said forward section.

FRANK H. WILLIAMS.
